Primary Examiner — Mitchell Siegel*(74) Attorney, Agent, or Firm* — Michael E. ZallCLAIM

The ornamental design for a putter head, as shown and described.

DESCRIPTION

FIG. 1 is a perspective view of my putter head embodying my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines in the figures depict environmental subject matter only and forms no part of the claimed design.
